(57) **CLAIM**

The ornamental design for a pet cage, as shown and described.

DESCRIPTION

FIG. 1 is a front view of a pet cage showing my new design; FIG. 2 is a rear view of the pet cage of FIG. 1;

FIG. 3 is a left side view of the pet cage of FIG. 1;

FIG. 4 is a right side view of the pet cage of FIG. 1;

FIG. 5 is a top view of the pet cage of FIG. 1;

FIG. 6 is a bottom view of the pet cage of FIG. 1;

FIG. 7 is a first perspective view of the pet cage of FIG. 1;

FIG. 8 is a second perspective view of the pet cage of FIG. 1; and,

FIG. 9 is a third perspective view of the pet cage of FIG. 1, with a tray taken out from the bottom of the pet cage.

The broken lines shown in the drawings are for the purpose of illustrating portions of the pet cage which form no part of the claimed design.

1 Claim, 9 Drawing Sheets
